Primary Examiner—Cathron C. Brooks(74) Attorney, Agent, or Firm—Wolf Block Schorr & Solis-Cohen LLP(57) CLAIM

I claim the ornamental design for an article of furniture and features thereroft, as shown and described.

DESCRIPTION

FIG. 1 is a perspective view of an article of furniture and features thereof showing my new design;

FIG. 2 is a front elevational view thereof;

FIG. 3 is a left side view thereof, the right side thereof being symmetrical with the left side; and,

FIG. 4 is a top plan view thereof.

The bottom of the article of furniture and features thereof is flat and unornamented. The broken lines are for illustrative purposes only and form no part of the claimed design.
